UNITED STATES PATENT OFFICE.

JAMES M. KEENE, OF WAUREGAN, CONNECTICUT.

APPARATUS FOR CLAMPING AND STRETCHING LEATHER AND OTHER MATERIAL.

SPECIFICATION forming part of Letters Patent No. 345,699, dated July 20, 1886.

Application filed January 22, 1886. Serial No. 189,363. (No model.)

To all whom it may concern:

Be it known that I, JAMES M. KEENE, a citizen of the United States, residing at Wau-
regan, Windham county, Connecticut, have
5 invented certain new and useful Improvements
in Devices for Clamping and Stretching Leath-
er on Cylinders, which improvements are fully
set forth and described in the following speci-
fication, reference being had to the accompa-
10 ny drawings, in which—

Figure 1 is a perspective view of my newly-
invented device, and Fig. 2 is a vertical longi-
tudinal section through the center of said de-
vice.

15 My invention relates to that class of clamps
used to stretch straps of leather, card-clothing
or similar material around the periphery of
rolls or cylinders of considerable size—as, for
example, in the covering of cylinders of card-
20 ing-machines, and also in the manufacture of
leather-covered polishing-wheels.

25 My object is to produce a cheaply-con-
structed device in which shall be combined a
strong clamp to hold the end of a strap, pow-
erful leverage to draw said strap tightly
30 around the roll or wheel, and which shall also
be so constructed that it will adapt itself to
wheels of different diameters.

35 In the covering of carding-machine cylin-
ders it is especially desirable that the so-
called “card-clothing” be drawn tightly and
smoothly around the cylinder, and also held
40 in place until fastened. This is also true of
that class of polishing-wheels in which a strip
of leather or walrus-hide is stretched around
45 and glued to the periphery of a wooden wheel.

Referring to the annexed drawings, the let-
ter *a* represents a metallic bar having one end
hinged within a lever-handle, *b*, whose longer
45 arm is formed as an operating-handle, and
whose lower (shorter) arm is considerably flat-
tened, as at *c*, and is provided in its end with
a series of spurs or pins, *d*. Hinged in lever
50 *b*, above the bar *a*, is a pawl, *e*, whose free end
is adapted to engage ratchet-teeth *f*, cut on
the upper side of bar *a*. In order to obtain
a finer adjustment I have hung on pawl *e* an
auxiliary pawl, *h*, which in practice serves the
55 same purpose as finer ratchet-teeth, the action
of said auxiliary pawl occurring between the
engagements of the principal pawl *e*.

The letter *i* represents a cast-metal piece,
one of whose ends is hinged to bar *a*, above
described, the opposite end being extended
laterally and formed with an angular jaw, *k*,
55 which coacts with a movable jaw, *m*, to grasp
and hold the end of a strap while in the act
of stretching it, as I shall refer to hereinafter.
The lower edge of jaw *k* is formed with a
ledge, *n*, extending the entire length of said
jaw.

The movable jaw *m* conforms in shape to
the outer face of the fixed jaw, and is pro-
vided with a rod, *o*, extending diagonally up
through the piece *i*, being held and operated
65 by a thumb-nut, *p*, as will be understood by
reference to the drawings.

On the outer face of piece *i* is an integral
lug, *s*, which, when the jaws are assembled,
extends through an opening, *t*, in jaw *m*, form-
70 ing a dowel to keep said jaw *m* in position
when not fastened by the thumb-nut.

My device is operated as follows: Jaws *k*
and *m* are opened until they will receive an end
of the strap to be stretched, the other end
75 having been already secured to the wooden
roll or cylinder. Thumb-nut *p* is now turned
home, thus causing said jaws to grasp said
strap firmly. The spurs *d* are then embedded
in the periphery of the wooden cylinder, with
80 the pawls thrown well inward on the ratchets
f, as shown. It will now be obvious that if
the handle of lever *b* is forced outward the
jaws *k* and *m* will follow the movement, drawing
85 the strap tightly around the cylinder, in
which position it is held by the pawls, which
act automatically as the lever-handle is moved
outward.

After properly securing the strap to the
cylinder the pawls are thrown out of engage-
90 ment and jaws *k* and *m* are opened to release the
end of the strap.

With the exception of the hinge-pins and
rod *o*, the several parts may be made of cast
metal, (preferably of malleable iron.)

Having thus described my invention, I claim
as new and wish to secure by Letters Patent—

A device for stretching leather or similar
flexible material on curved surfaces, consist-
ing of a body portion formed of two sections
100 pivotally connected, as described, one section
having on its outer end adjustable jaws capa-

able of grasping and holding the material to be stretched, the outer end of the companion section being hinged by a fulcrum-pin to a lever whose shorter arm is provided with

spurs, as described, the elements named being combined with each other, and with a pawl hinged in the said lever and adapted to en-

gage a series of ratchet-teeth in the body-section, all being substantially as herein set forth.

JAMES M. KEENE.
